UNITED STATES PATENT OFFICE.

ARTHUR SCHIMMEL, OF EVANSVILLE, INDIANA.

STREET-INDICATOR.

No. 833,248.

Specification of Letters Patent.

Patented Oct. 16, 1906.

Application filed March 2, 1906. Serial No. 303,848.

To all whom it may concern:

Be it known that I, ARTHUR SCHIMMEL, a citizen of the United States, residing at Evansville, in the county of Vanderburg, State of Indiana, have invented certain new and useful Improvements in Street-Indicators, of which the following is a specification, reference being had therein to the accompanying drawings.

10 This invention relates to a street-indicator, and particularly to an apparatus of that character embodying a web carried upon oppositely-disposed spools and wound from one to the other thereof.

15 The invention has for an object to provide a novel and improved construction and arrangement of driving means for rotating one of the spools to draw the web from the opposite spool, together with means for shifting this driving means to permit rewinding of the spool and means for effecting an intermittent release of the spools and web carried thereby.

20 Other and further objects and advantages of the invention will be hereinafter fully set forth and the novel features thereof defined by the appended claims.

In the drawings, Figure 1 is a central cross-section through the indicator. Fig. 2 is an end view thereof looking from the right of Fig. 1. Fig. 3 is a vertical section on line 3-3, Fig. 1. Fig. 4 is a detail perspective of the casing opposite the sight-opening for the web, and Fig. 5 is a similar view of the means for connecting the web to the hub of the spool or roll.

Like numerals of reference indicate like parts in the several figures of the drawings.

The numeral 1 designates a supporting frame or casting of any desired character provided at its upper and lower portion with elongated bearing-boxes 2, adapted to receive a journal or shaft 3, extending inward from each of the web-spools 4 and held in proper position by means of a collar 5 upon the inner end of the shaft 3. The spools carried by the shaft consist of the central hub 6, provided with a slot or recess 7, extending longitudinally thereof and in which the metallic strip 8, carried by the end of the web 9, is adapted to be secured. The web is supplied with the names of the streets or stations to be indicated in the usual manner. Secured to the opposite ends of this hub are the spool-heads 10, the outer one of which is held in position by the washer 11, seated

upon a squared portion of the shaft 3, and a clamp-nut 12, threaded to the end of the shaft beyond said squared portion. The inner head is provided with apertures 13 therein, disposed at opposite points and adapted to engage points or projections 14, carried by the gear 15, secured upon the shaft 3 of the lower spool, and the gear 16, secured upon the shaft 3 of the upper spool. The construction of each of the spools is similar, with the exception that the driving-gear 16 upon the upper-spool shaft 3 is provided with an inward projection or lug 17 to coöperate with a latch or holding-pawl 18, which is pivotally mounted at 19 and normally held 65 in engagement with the lug 17 by a spring 20.

For the purpose of permitting the intermittent movement of the apparatus an electromagnet 21 is disposed above the holding-pawl and connected, by means of wires 22, 75 with a suitable switch 23 and battery or other source of power 24, so that upon the closing of the switch the magnet will be energized and the pawl lifted to permit a rotation of the gear 16, which then again engages the pawl, as circuit is only momentarily made by the switch.

Any desired form of motor may be used for the purpose of driving or rotating these spools; but for the purpose of illustration I have shown an electric motor 25, mounted upon the carriage 26, which is disposed to slide or reciprocate within the ways 27, carried by the casting 1. The shaft 28 of this motor extends through a slot 29 in the casting 1 and is provided with a driving-pinion 30, adapted to be shifted upward into engagement with the gear 16 or downward into contact with the intermediate pinion 31, which is carried by the stub-shaft 32 and 95 meshes with the gear 15 of the lower spool. This latter position of gearing is that normally used to rotate the web for the purpose of exhibiting the streets or stations named thereon. In order to prevent a slack in the movement of the web, a friction-wheel 33 is secured to the stub-shaft 32 and adapted to contact with a friction-brake 34, adjustably mounted in a lug 35 by means of a screw 36, as shown in Figs. 1 and 2.

The preferable construction of motor is a slow electric motor to which current is carried by means of the wires 37 connected therewith and with any suitable source of power, as indicated at 38, which in the case 110

of an electric car may be taken in shunt from the motive power or from storage or other batteries thereon.

The motor may be shifted in its ways by any desired connection—for instance, by means of the lever 39, pivoted at 40 and provided with a crank member 41, connected by a pivoted link 42 with the carriage 26 of the motor. This lever is adapted to be secured in any desired position by means of the latch-pin 43 carried thereby and extending therethrough, so as to engage in any one of a series of apertures 44, carried by a portion 45 of the casting, said pins being under the tension of the spring 46, passing beneath the keeper 47 on the lever. It will be seen that the latch 43 when withdrawn from the aperture will release and permit a movement of the lever to shift the motor and its gear into engagement with either of the spool-driving connections.

The parts so far described may be inclosed in any desired construction of frame or casing—for instance, as shown at 48—the front thereof being provided with a suitably glazed aperture 49, across which the web 9 from the spools extends, and for the purpose of guiding this web in its passage the holder 50 is provided and preferably formed of sheet material, as shown at Fig. 4. This holder is mounted by means of lugs 51, comprising flanges at opposite sides thereof, which engage the tracks or ways 52, carried by the inner face of the casing, and the edges 35 of the holder over which the web passes are rounded by curving back a portion thereof, as shown at 53, so as to prevent injury or cutting of the web. This mounting also permits the holder to be readily slipped from 40 engagement with its retaining-ways and removed with the web and spools, upon which the same is wound when it is desired to insert another or different web in the indicator—for instance, when the route of travel of 45 the car is changed. It will also be seen that these spools may be directly withdrawn from their driving-shaft by simply removing the thumb-nuts from the end thereof.

In the operation of the invention it will be seen that the motor and its gear are shifted from the intermediate position (shown in Fig. 1) into engagement with the lower driving-gear, so as to impart a slow motion to the lower spool when circuit is successively completed to lift the holding-pawl engaging the driving-gear of the upper spool, which at this time remains idle. When the route has been completed and it is desired to reverse or rewind the web, the motor is shifted into engagement with the upper spool and the holding-pawl held by its magnet out of the path of its lug, so that the web may be rewound at a greater speed. The means for mounting the motor to reciprocate or travel in a straight path causes the gears to directly ap-

proach each other in meshing and obviates the difficulties present in a swinging structure, while it embodies the utmost simplicity in construction and efficiency in operation.

Having now described my invention and set forth its merits, what I claim, and desire to secure by Letters Patent, is—

1. In an indicator, opposite spools, a web carried thereby, a motor-carriage slidingly mounted intermediate of the spools, driving-gears carried by said spools, a motor upon said carriage provided with a gear disposed to travel in a straight line relative to the axis of the spool-gears to drive either thereof, and means for shifting said carriage. 80

2. In an indicator, opposite spools, a web carried thereby, a motor-carriage slidingly mounted intermediate of the spools, driving-gears carried by said spools, a motor upon said carriage provided with a gear disposed to travel in a straight line relative to the axis of the spool-gears to drive either thereof, means for shifting said carriage, a projection carried by one of said spools, a retaining device disposed in the path of travel of said projection, and means for withdrawing said device from said path. 85

3. In an indicator, opposite spools, a web carried thereby, a motor-carriage slidingly mounted intermediate of the spools, driving-gears carried by said spools, an electric motor upon said carriage provided with a gear disposed to travel in a straight line relative to the axis of the spool-gears to drive either thereof, means for shifting said carriage, a projection carried by one of said spools, a retaining device disposed in the path of travel of said projection, an electromagnet adapted to withdraw said device from said path, a circuit from said magnet, and an independent driving-circuit. 95

4. In an indicator, opposite spools, a web carried thereby, a motor-carriage disposed intermediate of the spools, a track or way for said carriage, an operating-lever for shifting said carriage, a gear carried by the shaft of said motor and co-operating driving-gears carried by the shafts of said spools. 110

5. In an indicator, opposite spools, a web carried thereby, a motor-carriage disposed intermediate of said spools, a track or way for said carriage, an operating-lever for shifting said carriage, a gear carried by the shaft of said motor, co-operating driving-gears carried by the shafts of said spools, a projecting lug carried by one of the spool-gears, and an electrically-controlled pawl adapted to engage said lug and hold the gears against movement. 115

6. In an indicator, a spool having one of its heads provided with recesses therein, a driving-shaft for said spool mounted in a bearing, a driving-gear secured to said shaft, pins projecting from one face of said gear to enter said recesses when the spool-head 120

contacts with the gear, a rectangular seat upon the outer end of said shaft, a washer disposed upon said seat in contact with the outer head of the spool, and a clamping-nut 5 threaded upon the end of said shaft.

7. In an indicator, a web, spools therefor provided with driving-gears, a frame provided with a track, a motor-carriage mounted to slide upon said track and provided with a 10 gear to drive said spool-gears, a pivoted lever mounted upon the indicator-casing adjacent to said carriage, and a link connection between said lever and carriage.

8. In an indicator, a web, spools therefor 15 provided with driving-gears, a frame provided with a track, a motor-carriage mounted to slide upon said track and provided with a gear to drive said spool-gears, a pivoted lever mounted upon the indicator-casing adjacent 20 to said carriage, a link connection between said lever and carriage, and a spring holding-latch carried by the free end of said lever to engage said casing.

9. In an indicator, a supporting-frame 25 comprising elongated bearings at opposite portions thereof, spool-shafts mounted in said bearings and provided with driving-

gears, parallel ways provided upon said frame, a shiftable motor mounted to slide in said ways intermediate of said spool-shafts 30 and provided with a driving-shaft in a slotted way in said frame, and a driving-gear carried by the motor-shaft.

10. In an indicator, a supporting-frame 35 comprising elongated bearings at opposite portions thereof, spool-shafts mounted in said bearings and provided with driving-gears, a shiftable motor mounted intermediate of said spool-shafts and provided with a driving-shaft in a slotted way in said frame, 40 a driving-gear carried by the motor-shaft, an intermediate gear mounted in the frame between the motor-gear and one of the spool-gears, a disk carried by the shaft of the intermediate gear, a friction-shoe adapted to engage said disk, and an adjusting-screw for said shoe.

In testimony whereof I affix my signature in presence of two witnesses.

ARTHUR SCHIMMEL.
